UNITED STATES PATENT OFFICE

167,285

STRAINER FOR A SURFACE DRAIN

John H. Schmid, Erie, Pa., assignor to J. A. Zurn
Manufacturing Company, Erie, Pa., a corpora-
tion of Pennsylvania

Application April 17, 1950, Serial No. 9,265

Term of patent 14 years

(Cl. D91—3)

To all whom it may concern:

Be it known that I, John H. Schmid, a citizen of the United States, residing at Erie, in the county of Erie and State of Pennsylvania, have invented a new, original, and ornamental Design for a Strainer for a Surface Drain, of which the following is a specification, reference being had to the accompanying drawing forming part thereof.

In the drawing

Fig. 1 is a top plan view of one-half of a strainer for a surface drain, showing my new design, the other half being a duplicate thereof; and

Fig. 2 is a side elevational view thereof.

I claim:

The ornamental design for a strainer for a surface drain, as shown and described.

JOHN H. SCHMID.
